United States Patent Office

Des. 231,053
Patented Apr. 2, 1974

231,053

BELT

Delores Bryant, 936 West End Ave.,
New York, N.Y. 10025

Filed Nov. 30, 1971, Ser. No. 203,506

Term of patent 14 years

Int. Cl. D2—07

U.S. Cl. D2—380

FIG. 1

FIG. 1 is a front perspective view of a belt embodying my design;

FIG. 2 is a side elevational view thereof; and

FIG. 3 is a rear elevational view.

I claim:

The ornamental design for a belt, substantially as shown.
